F. BUCHER.

Heating Stove.

No. 24,192.

Patented May 31, 1859.

UNITED STATES PATENT OFFICE.

FREDERICK BUCHER, OF COLUMBIA, PENNSYLVANIA.

STOVE.

Specification of Letters Patent No. 24,192, dated May 31, 1859.

To all whom it may concern:

Be it known that I, FREDERICK BUCHER, of Columbia, in the county of Lancaster and State of Pennsylvania, have invented a new and useful Improvement in Coal - Stoves; and I do hereby declare the following to be a full, clear, and exact description of the construction and operation of the same, reference being had to the accompanying drawings, making a part of this specification, in which—

Figure 1, represents an elevation of the stove in perspective. Fig. 2, represents the portion of the stove above the fire box, with its cover or top removed. Fig. 3, represents a vertical section through that portion of the stove shown in Fig. 2. Figs. 4, 5, 6 and 7, represent detached portions of the stove.

To enable others skilled in the art to make and use my invention, I will proceed to describe the same with reference to the drawings.

h, represents a base and *m*, a fire box of a stove which may be of any desirable form, 25 and ornamented or plain.

o, is the door for supplying fuel to the fire box. This part of the stove may be of cast iron, while the upper portions may be of sheet iron. Through the top of the fire box 30 or cylinder, and over the fire, may be placed a pipe or tube *d*, having small holes made in it, its object being to furnish atmospheric air in jets to the escaping products of combustion, and thus cause them to burn. Over 35 the fire box or cylinder there is a cap *a*, in the center of which there is a dome *c*, and around its perimeter a series of pipes *G*, which lead up into a radiating chamber *h*, and in which chamber there is a second 40 chamber or compartment as shown by Fig. 4, covered by a register or damper *e*. The object of this chamber and register is two-fold, as will be hereafter explained. A second series of pipes *G*, leads from this lower 45 chamber or radiator *h*, to an upper one of a similar kind, but instead of the dome *c* which does not make an open flue, these two chambers are connected by a pipe *f*, which leads from one of the inclosed chambers in 50 one radiator to the other inclosed chamber in the other one, but in or over the second inclosed chamber, the register or damper *e*,

is on top of said chamber, while in the radiator below, the register is on the bottom of said inclosed chamber. Over the upper 55 chamber may be a cover *p*, with an exit pipe *i* in it, with a close or partially open damper to regulate the draft. The registers *e* are made to cover or expose a portion of the flue pipes *G*, namely that portion which lead 60 from one inclosed chamber to the other. And when the openings in the registers *e*, are directly over the pipes *G*, then the draft from the fire box *m*, to the exit pipe *p*, is 65 direct. But when the registers *e* are turned 70 so as to cover the pipes *G*, it not only cuts off and separates the inclosed chambers from a direct passage through the stove, but causes some of the pipes *G*, to become diving flues, and to carry the heat and gases 75 back through the radiators where they may expend themselves, and thus their heating properties be saved.

When both registers are closed, the heat and gases take the direction shown by the 75 red arrows in Fig. 3, but when open as before stated then the draft is direct, but there is no radiation. By this arrangement I have great draft in starting the fire, and when it is burning, causing the whole upper part 80 of the stove to become radiating surface by simply drawing the registers *e* to cut off the direct draft and cause the gases to return back through *f*, and thence by the other series of pipes to escape to the chimney. 85

Through the radiators *h*, there may be openings *n*, for the heated air to radiate from.

Having thus fully described the nature and object of my invention, what I claim 90 therein as new and desire to secure by Letters Patent is—

In combination with the fire cylinder, the double radiators *h*, each inclosing an interior chamber and register, so that the draft 95 may be direct, or checked at pleasure in its passage through the stove, by which means I obtain much radiating surface, and economize much fuel, the whole being arranged substantially as herein represented.

FREDERICK BUCHER.
